[57] CLAIM

The ornamental design for an animal figure, as shown and described.

DESCRIPTION

FIG. 1 is a left side elevational view of the animal figure showing my new design, the right side elevational view being substantially a mirror image thereof;
FIG. 2 is a front elevational view of the animal figure;
FIG. 3 is a rear elevational view of the animal figure;
FIG. 4 is a top plan view of the animal figure; and
FIG. 5 is a bottom plan view of the animal figure.
